HOUSEHOLD TRASH CAN

John C. Rogers and Redding Sims,
New Orleans, La.

Application January 19, 1946, Serial No. 642,330

6 Claims. (Cl. 220—36)

1

This invention relates to a household trash can.

An object of the invention is to provide a container of the character described embodying an outer shell and an inner can within and spaced from the shell and removable therefrom with a cover hinged on the shell and completely closing the can with novel means including an accessible pedal for moving the cover either to open or closed position.

Another object of the invention is to provide a household utensil of the character described wherein the cover actuating mechanism, excepting the pedal, is completely enclosed between the can and the shell.

It is a further object of the invention to provide in a utensil of the character described cover actuating mechanism effective to move and maintain the cover in open position upon one operation of the pedal and to move the cover to closed position upon a succeeding actuation of the pedal.

A further feature of the invention resides in the provision of cover actuating means which includes a tension member, preferably a coil pull spring, which, upon operation of the pedal will automatically swing the cover to open position and maintain it open until the pedal is again operated whereupon the spring will insure the complete closing of the cover and maintain it in tightly closed position.

The invention also embodies a seal to securely close the space between the upper end of the can and the shell to prevent the entrance of foreign matter between the can and the shell.

It is a further object of the invention to provide a household utensil of the character described that is of very compact construction so that it can be conveniently used.

With the above and other objects in view the invention has particular relation to certain novel features of construction, operation and arrangement of parts, an example of which is given in this specification and illustrated in the accompanying drawings, wherein:

Figure 1 is a vertical, sectional view taken on the line 1—1 of Figure 4 showing the cover in closed position.

Figure 2 is a similar view showing the cover open.

Figure 3 is a side elevation of the utensil.

Figure 4 is a plan view partly broken away.

Figure 5 is an enlarged fragmentary horizontal sectional view taken on the line 5—5 of Figure 3.

Figure 6 is an enlarged vertical sectional view taken on the line 6—6 of Figure 4; and

Figure 7 is a perspective view of the inner can.

Referring now more particularly to the draw-

2

ings wherein like numerals of reference designate the same parts in each of the figures, the numeral 1 designates an outer shell which is substantially open at the bottom but which has the transverse 5 supporting bar 2 at the bottom of the shell whose ends are anchored to the front and rear wall of the shell. This bar forms a can support. The shell has a cover 3 hinged to the rear wall thereof.

In horizontal cross-section the shell is preferably substantially rectangular thus providing a flat rear wall which will fit closely against the wall of the room in which the utensil is located so as to prevent dust collection.

Around the top margin of the shell there is a 15 downwardly and inwardly converging seal ring 4.

Numeral 5 designates an inner can which is shaped to fit within the outer shell and rest on the supporting bar 2. The upper end of the can has an outwardly extended rim 6 which fits tightly 20 against the seal ring 4 when the inner can is in home position.

Fastened to one side of the shell, near the top thereof, there is an inside bracket 7 whose lowered end is spaced from the wall of the shell, as more 25 clearly shown in Figure 6, and whose upper end has an inwardly turned stop 8, for a purpose to be hereinafter stated.

Pivottally mounted on the lower end of the bracket 7 there is a toggle plate 9, one end of 30 which is provided with the upstanding lug 10 and whose other end is provided with the upstanding bumper 11. Beneath the pivot of the toggle plate it is provided with a lengthwise slot 12 whose ends terminate in the downwardly directed notches 13, 14.

Beneath the toggle plate 9 and in substantial 35 alignment therewith there is an actuating lever 15 one end of which is pivoted to the shell and whose other end 15a is outwardly turned and extends through a vertical slot 16 in the same side of the shell.

A tension member such as a coil spring 17 is connected, at one end, to the lug 10 and whose other end is connected to the actuating lever 15 near the pivoted end thereof and an actuating 45 link 18 is pivotally connected, at its lower end, to the free end of the lever 15 and this link extends up between the wall of the shell and the toggle plate and its other end 18a is overturned and works through the slot 12 and is adapted to engage 50 in the notches 13, 14 in a manner hereinafter explained.

Secured to one side of the cover 3, near its hinged end, there is a bracket 19 one end of which is spaced outwardly from the cover and is downwardly turned forming an ear 20. An actuating 55

link 21 is pivotally connected, at its upper end, to the ear 20 and it works through an elongated slot 22 in the seal ring 4 and its other end is pivotally connected to the corresponding end of the toggle plate 9 just beneath the bumper 11.

There is an equalizing lever 23 on the inside of the front wall of the shell at the bottom. One end of this equalizing lever is pivoted to the shell and curved to conform to the wall contour of the shell and its other end 23a is turned outwardly through the slot 16.

The ends 15a, 23a of the levers thus coincide, as shown in Figure 5, and pivotally connected to them there is the pedal 24. This pedal may be of any preferred construction. As shown it is formed of sheet metal with the downwardly turned outer and side margins and with the inwardly extended space lugs 25, 25 which embrace the outwardly turned lever ends 15a, 23a and which are pivoted thereto. As shown in Figure 6, the ends 15a, 23a of the levers extend inwardly into the pedal which rests on said ends.

With the shell cover 3 closed, as shown in Figure 1, upon a slight pressure on the pedal, the outwardly turned end 18a of the link 18 will be seated in the notch 13 and the toggle plate 9 will be rotated on its pivot. The spring 17 is under tension and when it passes center it will exert a pull on the toggle plate 9 and without effort on the part of the operator the cover 3 will be lifted to open position by the spring 17. The bumper 11 will eventually contact with the stop 8 to limit the range of movement of the cover, as indicated in Figure 2. When the pedal is released the overturned end 18a of the link 18 will be lifted, or unseated, from the notch 13, by the pull of the spring 17 acting on the lever 15 and as the position of the toggle plate 9 is reversed from the position shown in Figure 1 to the position shown in Figure 2 the overturned end 18a will move along the slot 12 in the direction indicated by the arrow in Figure 2 until the overturned end 18a is above the notch 14. When it is desired to close the cover 3 the pedal 24 may be again depressed causing the overturned end 18a of the link 18 to seat in the notch 14 and exert a pull on the toggle plate 9 moving it in a reverse direction and when the spring 17 has again passed center it will automatically operate to continue the movement of the cover 3 to closed position. Upon release of the pedal the pull of the spring 17 acting through the lever 15 and the link 18 will unseat the overturned end 18a from the notch 14 and thereupon said overturned end 18a will move along the slot 12 in the direction indicated by the arrow in Figure 1 until the parts assume their original position with the cover tightly closed.

The inner can 5 is provided with a pivoted bail 26 whereby it may be removed from and replaced in the shell.

The shell and can are preferably formed of sheet material such as sheet metal and the cover operating mechanism is also preferably formed of metal although it is to be understood that all of these parts may be formed of any suitable material.

The drawings and description are illustrative merely while the broad principle of the invention will be defined by the appended claims.

What we claim is:

1. A utensil comprising, a container, a cover pivotally mounted on the container, a member mounted to rotate on the container and having eccentric seats, oscillatable means on the con-

tainer accessible to an operator, a shiftable connector attached to said means and having means thereon engageable alternately with said seats, as the oscillatable means is successively operated to oscillate said member, a connector attached to the cover and eccentrically connected to said member and effective to move the cover to open and closed position as said member oscillates, and yieldable means connected to said member and arranged to impart the final cover-opening movement to said member.

2. A utensil comprising, a container, a cover pivotally mounted on the container, a member mounted to rotate on the container and having eccentric seats, oscillatable means on the container accessible to an operator, a shiftable connector attached to said means, means on the connector engageable alternately with said seats, as the oscillatable means is successively operated to oscillate said member, a connector attached to the cover and eccentrically connected to said member and effective to move the cover to open and closed position as said member oscillates, and a tension element connected to said oscillatable means and also connected to said member at a point which is eccentric of the axis of rotation of said member.

3. A utensil of the character described comprising, a container, a cover hinged to the container, a toggle plate mounted to rotate on the container and having eccentric seats on one side of the pivot, a lever on the container accessible to an operator, a yieldable member connected to said lever and to the toggle plate on the other side of the pivot, a shiftable link pivotally connected to said lever and having means thereon to alternately engage said seats as the lever is successively operated to oscillate said toggle plates, a link pivotally connected to the cover and eccentrically connected to said plate and effective to move the cover to open and closed position as said member oscillates, and means for limiting the movement of the cover toward open position.

4. A utensil comprising, a container having a side slot at its lower end, a cover hinged to the container, a toggle plate mounted to rotate on the container and having a lengthwise slot beneath its pivot whose ends terminate in downwardly directed notches, a stop fastened to the wall of the container, an upstanding lug on one end of the toggle plate and a bumper on the other end of said plate, said lug and bumper being arranged on opposite sides of the stop, an actuating lever one end of which is pivoted to the container and whose other end is outwardly turned through said container slot, a tension member connected at one end to said lug and whose other end is connected to said lever, a link one end of which is pivotally connected to said lever and whose other end is overturned and works through the slot in the toggle plate and is engageable in said notches, a bracket secured to one side of the cover adjacent the hinge, one end of said bracket being spaced outwardly from the cover and downwardly turned forming an ear, an actuating link pivotally connected, at one end, to said ear and whose other end is pivotally connected to the toggle plate beneath said bumper.

5. A utensil comprising, a container having a side slot at its lower end, a cover hinged to the container, a toggle plate mounted to rotate on the container and having a lengthwise slot beneath its pivot whose ends terminate in downwardly directed notches, a stop fastened to the

wall of the container, an upstanding lug on one end of the toggle plate and a bumper on the other end of said plate, said lug and bumper being arranged on opposite sides of the stop, an actuating lever one end of which is pivoted to the container and whose other end is outwardly turned through said container slot, a tension member connected at one end to said lug and whose other end is connected to said lever, a link one end of which is pivotally connected to said lever and whose other end is overturned and works through the slot in the toggle plate and is engageable in said notches, a bracket secured to one side of the cover adjacent the hinge, one end of said bracket being spaced outwardly from the cover and downwardly turned forming an ear, an actuating link pivotally connected, at one end, to said ear and whose other end is pivotally connected to the toggle plate beneath said bumper, an equalizing lever pivotally connected to the front wall of the container on the inside thereof adjacent the bottom of the container and whose other end is outwardly turned through the slot in the container wall, the adjacent ends of the actuating lever and equalizing lever being in coinciding relation and a pedal accessible to an operator and pivotally connected to, and resting upon, said coinciding ends.

6. A utensil comprising, a container having a side slot at its lower end, a cover hinged to the container, a toggle plate mounted to rotate on the container and having a lengthwise bearing beneath its pivot whose ends terminate in downwardly directed notches, an actuating lever one

end of which is pivoted to the container and whose other end is outwardly turned through said slot, a tension member connected at one end to said toggle plate and whose other end is connected to said lever, a link one end of which is pivotally connected to said lever and whose other end is overturned and works in said bearing and is engageable in said notches, an actuating link pivotally connected, at one end, to the cover and whose other end is pivotally connected to an end of the toggle plate, an equalizing lever pivotally connected to the front wall of the container on the inside thereof adjacent the bottom of the container and whose other end is outwardly turned through the slot in the container wall, the adjacent ends of the actuating lever and equalizing lever being in coinciding relation and a pedal accessible to an operator and mounted on said coinciding ends.
